Attorneys.

UNITED STATES PATENT OFFICE.

WILLIAM S. PETERSON, OF GREAT FALLS, MONTANA.

RING-TURNING DEVICE.

Application filed June 13, 1921. Serial No. 477,342.

To all whom it may concern:

Be it known that I, WILLIAM S. PETERSON, a citizen of the United States, residing at Great Falls, in the county of Cascade 5 and State of Montana, have invented certain new and useful Improvements in Ring-Turning Devices, of which the following is a specification.

The invention relates to ring-turning devices and more particularly for use in turning collector rings.

It is the main object of the invention to provide a mechanism which may be applied to the brush-holder standard of a rotary 15 converter or other machine having collector rings so that the latter may be turned without removing the brush-holder standard or other large parts from the machine.

The invention essentially comprises a 20 turning tool, a support adapted to be attached to the brush-holder standard, carriage mechanism and means between the carriage mechanism and the tool for bringing the tool into and out of engagement with 25 the ring.

For a full understanding of the invention reference is made to the accompanying drawings in which—

Fig. 1 is a fragmentary side elevation of 30 a device to which the invention is applied;

Fig. 2 is a perspective view of a device embodying the invention;

Figs. 3 and 4 are side elevation and end view respectively of the device shown in 35 Fig. 2; and

Figs. 5, 6 and 7 are perspective views of certain details.

In Fig. 1 of the drawings 1 represents the ring surface of a collector and 2 the brush-holder standard mounted upon a support 3. The brush-holder standard, which is of the usual design, has a plurality of groups of perforations 4 for adjustably mounting the brush-holders 5.

The device embodying the invention is designed to be mounted on the brush-holder standard in lieu of a brush-holder.

As indicated on a larger scale in Figs. 2, 3 and 4, the operating mechanism of the 50 ring turner is mounted upon a bracket 6 having holes 7 spaced to register with the holes 4 on the brush-holder standard.

The bracket 6 carries a dove-tailed slide bed 8 for the cross-feed carriage 9.

The cross-feed carriage 9, in turn carries

the slide bed 10 for the cutting feed carriage 11.

At the front of the bed 8 is attached a head plate 12 affording a bearing for the feed screw 13. To the front of the carriage 11 is attached a plate 14 affording a bearing for the feed screw 15. The screw 13 extends into the carriage 9 and the screw 15 into the bed 10. When screw 13 is rotated the carriage 9 is moved relatively to the bed 8 and when screw 15 is rotated the carriage 11 is moved relatively to the bed 10.

The relation of the cross-feed mechanism and the cutting feed mechanism is well understood from the prior art and need not be further described.

Upon the carriage 11 is pivotally mounted the tool holder. This tool holder comprises a hinge plate 18, a tool post 19, a tool post washer 20, an adjustment shim 21 and a clamping screw 22. The upper surface of the washer 20 is spherically concaved and the lower surface of the shim 21 is similarly curved to be angularly adjustable thereon.

The lower face of the hinge plate 18 is recessed to receive the base flange 19^a of the tool post, the latter extending upwardly through an aperture in the hinge plate, as clearly shown in Fig. 5.

The hinge plate 18 has two perforated depending lugs 17 seated in lateral recesses or pockets 16 in the carriage 11. The pockets 16 have diverging walls to allow of angular movement of the hinge plate relatively to the carriage 11.

A pintle 23 extends through a bore 24 and through the apertures 17^a of the lugs 17 whereby the hinge plate is pivotally connected to the carriage 11.

To the hinge plate 18 is secured a forked lever 25 for turning the tool holder about the pintle 23.

The tool post has a central slot for receiving the tool 27.

In assembling the tool holder parts, the post 19 is passed upwardly through the hinge plate 18 and then the hinge plate is pivotally connected to the carriage 11. The dished washer 20 is then passed over the free end of the post and the shim placed into the slot 26 of the post. The tool 27 may now be clamped upon the shim by means of the screw 22. Due to the dished upper surface of the washer 20 and the

curved lower surface of the shim the tool may be adjusted in any desired inclined position within a limited range of adjustment.

5 To attach the ring turner to the brush holder standard, it is merely necessary to remove two adjacent brush-holders to make room for the ring turner.

The operation of the carriages 9 and 11 10 for carrying on the turning operation is obvious. The tool is adjusted to the desired position by the screws 13 and 15 which may be manipulated by small hand wheels or a key wrench (not shown).

15 When ready to cut, pressure is exerted on handle 25^a of the lever 25 so as to cause the tool post hinge plate 18 to bear firmly upon its seat on feed carriage 11.

If the tool should have a tendency to 20 gouge due to a mistake on the part of the operator, the frictional resistance of the tool upon the collector ring during the rotary movement of the latter will tend to lift the tool point and throw it upward and backward and a sudden pull would cause the operator to release the handle and free the tool.

It is thus a special advantage of the arrangement described that gouging is practically eliminated and injury avoided.

Another advantage of the device is the possibility of withdrawing the tool without changing the adjustment of the parts determining the operative position of the 35 tool.

It is another advantage of the arrangement that no external driving power is required since the converter or other machine can be started and operated in the usual 40 manner and then disconnected from the line when a sufficient speed is attained, allowing the ring to be turned while the machine is running idle. The momentum imparted to the machine is sufficient to make substantial cuts.

Another material advantage lies in the possibility of turning rings without removing the brush holder standard—it being merely necessary to remove two brush-holders,—or without building up a special support for the cutting tool and its operating mechanism.

It is understood that within the scope of the invention various changes may be made. 55 The particular form of the device is merely referred to as a preferred embodiment of the invention.

I claim:

1 A ring-turning mechanism including a 60 bracket constructed and arranged to be attached to the brush-holder standard of an electric machine, a tool holder, means for

moving the tool holder transversely of the bracket and at right angle thereto and means for quickly moving the tool into 65 and out of cutting position relatively to the said mechanism.

2. A ring-turning mechanism including a bracket constructed and arranged to be attached to the brush-holder standard of an 70 electric machine, a tool holder, cross-feed and cutting feed mechanism on the bracket for moving the tool holder into and out of operative position and a pivotal connection 75 between the tool holder and said mechanism for quickly moving the tool holder into and out of cutting position relatively to the said mechanism.

3. A ring-turning mechanism including a bracket constructed and arranged to be attached to the brush-holder standard of an 80 electric machine, a cross-feed mechanism mounted upon the bracket, a cutting feed mechanism mounted upon the cross-feed mechanism and a tool holder pivotally mounted upon the cutting feed mechanism.

4. A ring-turning mechanism including a bracket-constructed and arranged to be attached to the brush-holder standard of an 85 electric machine, a tool holder, mechanism 90 for adjusting the position of the tool holder upon the bracket to bring the holder into and out of cutting position, a hinge connection between the tool holder and the said mechanism and a lever for moving the tool 95 holder about the hinge connection.

5. A ring-turning mechanism including a bracket constructed and arranged to be attached to the brush holder standard of an 100 electric machine, a tool holder, mechanism for adjusting the position of the tool holder upon the bracket to bring the holder into and out of cutting position, and means between the said mechanism and the tool holder for moving the latter into and out of a fixed relation to the former whereby the tool can be detached from the work and returned to its previous cutting position without changing the position of the said mechanism.

6. A ring-turning mechanism including a bracket constructed and arranged to be attached to the brush-holder standard of an 105 electric machine, a tool holder, mechanism for adjusting the position of the tool holder upon the bracket to bring the holder into and out of cutting position, a plate pivotally connected to said mechanism and carrying the tool holder and a lever connected to the 110 said plate for moving the latter about its 115 pivot.

In testimony whereof, I affix my signature.

WILLIAM S. PETERSON.
